IMPROVEMENT IN SKATES.

H. W. DOPP AND CHARLES P. WEISS, OF BUFFALO, NEW YORK, ASSIGNEES TO THEMSELVES AND J. FORSYTH, OF THE SAME PLACE.

Letters Patent No. 59,899, dated November 20, 1866.

SPECIFICATION.

TO ALL WHOM IT MAY CONCERN:

Be it known that we, H. W. DOPP, and CHARLES P. WEISS, of the city of Buffalo, county of Erie, and State of New York, have invented a new and improved skate; and we do hereby declare that the following is a full and exact description thereof, reference being had to the accompanying drawings, and to the letters of reference marked thereon.

Figure 1 is a perspective view of the model.

A is the foot-plate secured to the runner; B B are two angle levers, having their fulcrum attached to the foot-plate A. These are provided on one end with two movable jaws C C, and are connected at the other end to a connecting rod D; C C are two jaws on levers B B. These are movable, independent of said levers, for the purpose of accommodating themselves to the shape of the boot. They are intended to clamp the sole between them, so as to hold the boot firmly to the foot-plate; D D is a connecting rod, having an end secured to the two levers B B, and the other end to a lever E. It is provided with a coupling, d, in its middle, by which the levers B B and jaws C C are adjusted, so that said jaws may at any time be set to fit the sole of the boot exactly. This coupling is provided through its centre with a right and left hand screw thread, into which D D are secured; by turning said coupling, the rod may be lengthened or shortened. E is a lever having its fulcrum secured to the runner, and to which D and H are connected. This gives motion to D and H; F is the heel-plate, fastened to the runner; G is a lever arrangement furnished with a toothed plate, the whole being secured to the heel-plate. It is designed to grip the heel of the boot, and pull it down to the plate F. Motion and power is given to G by means of E; H is a connecting rod, having an end fastened to E, and the other end fastened to G. This has a coupling in its middle for the purpose of lengthening and shortening said rod. It is constructed and operated like d.

To fasten and use this skate, place the foot on to F and A, then pull up the lever E until it snaps into a notch made for that purpose in the upright between the runner and foot-plate.

1. We claim the combination of the self-adjusting jaws C C, levers B B, and rod D, as described.
2. We claim the lever arrangements E and G, in combination with rod H.

H. WM. DOPP,
CHARLES P. WEISS.
